DESIGN FOR A HAND BOUQUET HOLDER OR ANALOGOUS ARTICLE

Chris H. Larsen, Chicago, Ill.

Application June 4, 1941, Serial No. 101,291

Term of patent 7 years

To all whom it may concern:

Be it known that I, Chris H. Larsen, a citizen of the United States residing at Chicago, in the county of Cook and State of Illinois, have invented a new, original, and ornamental Design for a Hand Bouquet Holder or Analogous Article, of which the following is a specification, reference being had to the accompanying drawing, forming a part thereof.

In the drawing,

Fig. 1 is a side elevational view of a hand bouquet holder, showing my new design;

Fig. 2 is a bottom plan view thereof.

I claim:

The ornamental design for a hand bouquet holder or analogous article, as shown.

CHRIS H. LARSEN.
